IGNITION CONTROL SYSTEM

Francis C. Pezzolo, Santa Clara County, Calif.

Application September 17, 1936, Serial No. 101,272

5 Claims. (Cl. 290—38)

The invention relates to an ignition system for internal combustion, or gas, engines having electrically operated starting motors.

A general object of the invention is to provide an electrical ignition circuit which is arranged to be closed only while the engine is being turned over by the starting motor or is self-operating in a normal manner.

A more specific object is to provide for the engine control of the ignition circuit in the described manner by utilizing a vacuum which results from the actuation of the engine.

Another object is to provide a normally open ignition circuit which may not be accidentally left closed while the engine is not operating.

An added object is to provide for the automatic opening of the ignition circuit in the event that the engine should backfire or start a backward rotation from any cause.

20 A further object is to provide for manually opening the ignition circuit while the engine is operating, whereby to stop the engine.

Yet another object is to provide for an independent closing of the ignition circuit solely 25 while the starting motor is energized.

The invention possesses other objects and features of advantage, some of which, with the foregoing will be set forth or be apparent in the following description of the invention, and in the 30 accompanying drawing in which,

Figure 1 is a diagrammatic presentation of the control system of my invention.

Figure 2 shows the system as applied in association with an internal combustion engine which 35 is arranged to provide the motive power for a self-propelled vehicle.

As particularly illustrated in Figure 2, the ignition control system of present invention is shown as associated with an internal combustion 40 engine 4 which is mounted in a fragmentarily shown vehicle wherein the operator's compartment 6 is bounded in part by a floor 7, a dash board 8, and an instrument board or panel 9, all provided in a suitable arrangement and relation 45 thereto. It will be noted, however, that the present control system is applicable to other installations of internal combustion engines having electric ignition systems and electric starting motors.

50 A usual storage battery 11 is provided to supply operating energy to an engine-starting motor 12 through a starting circuit which includes a normally open switch 13 mounted on the vehicle floor 7 with a push button 14 thereof extending 55 into the compartment 6 for hand or foot actuation

by the operator of the vehicle to close the starter circuit against the resistance of a compression spring 15. The circuit connections include a lead 16 from the battery 11 to terminal of the switch 13, a lead 17 from the other terminal of the switch 13 to a motor terminal, and ground connections 18 and 19 respectively. The starting motor 12 is mechanically connected to the engine crank shaft through suitable gearing and clutch connections in a housing 20 whereby it is arranged to produce 10 operative actuations of the engine parts before the ignition is effective and the engine is self-operating.

Current for the ignition circuit is also derived from the battery 11, and said circuit includes a 15 pressure-controlled switch 21, a switch 22 which normally closes the ignition circuit thereat and is arranged for manual opening for a reason to be hereinafter brought out, a usual cam-operated timer switch 23, and the primary of a usual ignition coil 24. It will be understood that the ignition coil 24 is essentially a transformer, and that the secondary circuit thereof provides the energy at the engine spark plugs (not shown).

As shown in Figure 1, the switch 21 essentially 25 comprises a movable contact arm 25 which is engageable with a fixed contact 26 for closing the ignition circuit thereat. The arm 25 is connected to and controlled by the movements of a resilient diaphragm 27 which provides one wall of 30 a chamber 28 which is connected with the interior of the fuel intake manifold 29 of the engine by means of a pipe or tube 30.

The relations at the switch 21 are such that the switch arm 25 engages the contact 26 only when a sub-atmospheric pressure exists in the chamber 28 and manifold 29; the latter condition is understood to exist only while the engine is being turned over or actuated in its proper operative direction by the starting motor or while the engine is self-operating. It will thus be understood that the ignition circuit is arranged to be open at the switch 21 while the engine is not operating; in this manner, the ignition circuit may not then be closed, or left closed, as frequently happens with 45 manually operable ignition switches. As shown, the connections for the ignition circuit are provided by a lead 32 connecting the lead 16 to the arm 25 of the switch 21, a lead 33 from the contact 26 to one terminal of the switch 22, a lead 34 from the switch 22 to a terminal of the timer switch 23, a lead 35 from the other terminal of the switch 23 to the primary of the ignition coil 24, and a ground connection 36 from the coil 24.

Recalling that the ignition circuit is open at 55

the switch 21 unless a vacuum obtains in the engine manifold 29 by reason of the actuation of the engine in its normal rotative direction, it will be noted that either a backfire or a reverse rotation of the engine will create a positive pressure in the manifold and so open the ignition circuit at the pressure-controlled switch 21. In this manner, ignition ceases under backfire and/or engine reversal conditions, and the engine may 10 promptly come to rest for its restarting by energizing the starting motor 12.

It will now be noted that the switch 22 is mounted on the instrument board 9 and includes a movable contact arm 37 which normally engages a fixed contact 38 through the action of a tension spring 39. A push button 40 extends from the arm 37 and through the instrument board for manual engagement to displace the arm 37 to open the ignition circuit at the switch 22 20 whenever the operating engine is to be stopped. It will be understood that the normally closed switch 22 is opened solely as a means to stop the operation of the engine by opening the ignition circuit therefor.

25 Since the ignition circuit will be kept closed at the pressure-operated switch 21 by the suction in the manifold 29 as long as the engine is operating, a stopping of the engine requires that the ignition circuit must not be re-closed at the switch 22 until the engine movement is stopped, or substantially stopped.

In order to avoid the necessity for manually pressing the push button 32 until the engine has stopped, means are preferably provided for automatic operation to keep the ignition circuit open at the switch 22 until the engine has stopped and following a release of the push button by the operator.

As illustrated, the switch arm 37 is arranged 40 to engage a contact 42 following its disposal out of contact with the contact 38, and the contact 42 is connected with one terminal of a terminal of a solenoid 43 having its other terminal grounded. The solenoid 43 encloses a fixed core 44 and the switch arm 37 carries an armature 45 opposite, and normally spaced from, an end of the core 44. In this manner, while the pressure-controlled switch 21 is closed in the described manner, the current which would normally flow 45 through the ignition timer and coil is arranged to be shunted through the solenoid 43 to energize the same for retaining the arm 37 in its displaced position. It will be understood that the combination of the arm 37 and the contacts 38 and 42 constitutes a two-way switch.

55 Means are preferably provided for automatically closing the ignition system independently of the action of the switch 21 while, and only while, the starting motor circuit is energized, said means 60 being particularly shown as comprising a normally open electro-magnetic switch 47 which is operative to effect the independent closing of the ignition circuit while the starting motor is operative. The switch 47 is of the relay type and its 65 solenoid 48 is connected in parallel with the motor 12 whereby the solenoid is energized only when the starting motor circuit is closed at the switch 13. A fixed contact 49 of the switch 47 is connected to the lead 32 by means of a branch 70 lead 50, and the armature arm 51 of said switch is connected to the arm 37 of the switch 22 by means of a lead 52; in this manner, the closed relay circuit provides a shunt around the pressure-controlled switch 21 in the ignition circuit.

75 It will be understood that it is immaterial if both

of the switches 21 and 47 should be simultaneously closed, as might happen while the starting motor 12 is actuating the engine.

From the foregoing description taken in connection with the accompanying drawing, the advantages of the construction and method of operation will be readily understood by those skilled in the art to which the invention appertains. While I have described the features and the principles of operation of a structure which I 10 now consider to be a preferred embodiment of my invention, I desire to have it understood that the showing is primarily illustrative, and that such changes may be made, when desired, as fall within the scope of the following claims.

I claim:

1. In combination, an internal combustion engine, an electric ignition circuit for said engine having a circuit-closing switch therein, means operative solely by the actuated engine to close 20 said switch, means independent of said switch for manual actuation to open said ignition circuit for stopping the engine, and electro-magnetic means automatically operative to maintain said circuit-opening means fully operative while the engine 25 is stopping and said switch is closed.

2. In combination with an internal combustion engine having an electric ignition means, a source of electricity for said ignition means, an ignition circuit connecting the said source and the ignition means and including a normally open switch and a normally closed switch in series connection therein with the second switch operatively installed between the first switch and the ignition means, mechanism automatically operative by 35 the operating engine to close said ignition circuit at the first switch, manually controlled means to open the second switch while the engine is operating, and electro-magnetic means automatically operative to constantly maintain the opened 40 second switch in open condition solely while said mechanism is operative to close the ignition circuit.

3. In combination with an internal combustion engine having an electric ignition means, a source 45 of electricity for operating said ignition means, an ignition circuit connecting the electric source and the ignition means and including a normally open switch and a normally closed switch in series connection therein with the second switch 50 operatively installed between the first switch and the ignition means, a normally open branch of said circuit for providing a shunt around the ignition means, mechanism automatically operative by the operating engine to close said ignition 55 circuit at the first switch, manually controllable means to open the second switch and close the branch circuit, and means operable by the flow of current in said branch circuit when the same is closed to constantly maintain the second switch 60 in open condition with respect to the first circuit while said mechanism is operative to close the circuit at the first switch.

4. In combination with an internal combustion engine having an electric ignition means, a source 65 of electricity for operating said means, an ignition circuit connecting the electric source and the ignition means and including a normally open switch and a normally closed switch in series connection therein with the second switch 70 operatively installed between the first switch and the ignition means, mechanism automatically operative by the operating engine to close said first switch, a normally open branch of said circuit for providing a shunt around solely the ignition 75

means, a manually operative means to open the second switch and close the aforesaid branch of the circuit, an electric motor for energizing to actuate the engine at starting and having its energy circuit independent of said ignition circuit, a branch of the ignition circuit for providing a shunt around solely the first switch, a normally open switch in said last branch of the circuit, and means utilizing the energy circuit of the motor to close the last switch while said starting motor is energized.

5. In combination with an internal combustion engine, an ignition circuit having a normally open

circuit-closing switch therein, means operated solely by the actuated engine to close said switch, a normally closed second switch in said circuit, means constantly operative to yieldingly urge a closing of the second switch, a manually controllable means for actuation to open the second switch against the resistance of its said closing means, and means controlled entirely in accordance with the condition of the first switch to maintain the opened second switch in open condition against the resistance of its said closing means only while the first switch is closed.

FRANCIS C. PEZZOLO.
